UNITED STATES PATENT OFFICE.

CHRISTOPHER W. LEVALLEY, OF MILWAUKEE, WISCONSIN.

CONCRETE-MIXING APPARATUS.

1,230,731.

Specification of Letters Patent. Patented June 19, 1917.

Application filed October 19, 1912. Serial No. 726,895.

To all whom it may concern:

Be it known that I, CHRISTOPHER W. LEVALLEY, a citizen of the United States, residing at Milwaukee, in the county of Milwaukee and State of Wisconsin, have invented new and useful Improvements in Concrete-Mixing Apparatus, of which the following is a specification.

My invention relates to machines for mixing concrete of the rotary drum type and provided with tilting discharge spouts adapted when adjusted to one position to receive the mixed concrete and deliver it through the discharge opening outside of the machine, 10 and when adjusted to another position to be inactive or to operate to return the material being mixed toward the head or feed end of the drum. In operating concrete mixers of large size and great capacity, it has been found difficult to rapidly move the discharge spout thereof by hand, and it frequently requires the services of two men to shift the spout from inactive to discharge position, owing to the weight of the parts to be moved, 20 and the fact that they are more or less clogged with cement and concrete, and, to the further fact that, as ordinarily arranged with a portion of the spout or chute extending well into the drum, a large amount 30 of material is being constantly delivered upon such inner portion when in its inactive or non-delivering position, and this material has to be moved when the spout is adjusted to deliver outward.

35 It is the object of my invention to combine with the discharge chute of a drum-mixing machine of the kind referred to, power-driven means for adjusting it.

I have illustrated in the accompanying 40 drawings two forms of apparatus embodying my invention, that the same may be better understood. In such drawings—

Figure 1 is a perspective view of a concrete mixing apparatus provided with one 45 form of my invention, the apparatus being viewed from the rear and one side.

Fig. 2 is a top plan view of part of the apparatus shown in Fig. 1.

Fig. 3 is a side elevation of the parts of 50 the apparatus shown in Fig. 2.

Fig. 4 is an elevation similar to Fig. 3, but illustrating a different embodiment of the invention.

Fig. 5 is a rear end view of the apparatus

illustrated in Fig. 4, parts of the machine being broken away.

Fig. 6 is a sectional view illustrating part of the automatic stop mechanism.

Fig. 7 is a detail face view of the cam employed in the stop mechanism.

In the drawings A designates the rotating drum of a concrete mixing machine. It is suitably supported by framework comprising sill pieces B, an upright frame C surrounding or straddling the drum, and a second upright frame D to one side of the drum in which is mounted the countershaft E of the driving mechanism.

F designates a discharge chute pivotally supported, at f, between the rear upright pieces c c of the frame C. This chute extends into the drum, through the discharge opening a thereof, sufficiently far to receive the mixed concrete, in a well known manner. Upon the countershaft E is a wheel G 75 adapted to be connected by belting of suitable character, with the motor, not shown, that operates the apparatus. Another wheel H upon the shaft is connected by a belt I with the drum in a well known manner.

Suitably supported by the uprights c is a rock shaft 2 carrying cranks 3, 3 that are connected by links 4, 4 with the discharge chute F. By the oscillation of this shaft the chute is adjusted. 5 is a stop bar extending 85 between the uprights c and upon which the crank arms 3 rest when the chute is adjusted to discharging position, and against which the chute itself bears when it is tilted into its other, inactive, position, that is, when inclining inward.

It has heretofore been customary to provide the shaft 2 with a handle arranged to be manually operated, but this arrangement, as already suggested, has been found to be objectionable, especially when applied to very large machines, and I have accordingly connected with such shaft power-driven mechanism, adapted to be controlled by the attendant of the machine, who usually takes 100 his place at the feed end of the drum in position to observe and control its movements and to regulate the water supply.

The power-driven mechanism for operating the delivery chute is preferably mounted 105 in the upper part of the framework D, which also supports the countershaft.

Referring particularly to Figs. 1, 2 and 3,

illustrating one form of my invention, 6 designates a horizontal shaft supported in the upper part of the frame D and connected with the countershaft E by a belt 7 or other suitable form of driving gear. Upon the shaft 6 are loosely mounted a pair of bevel pinions 8 8' so spaced apart as to properly mesh with a bevel wheel 9 upon the rock shaft 2 at diametrically opposite points. 10 The hubs of the bevel pinions are provided with clutch members 10 10', and between these is mounted a sliding clutch member 11 splined to the shaft 6 and arranged to be adjusted either to a position intermediate 15 between the clutch members 10 10' and out of engagement with both of them, or into engagement with one or the other of the clutch members of the bevel pinions. The shifting clutch member 11 is operated by a 20 lever 12 to which is connected a shifting rod 13 extending toward the front of the apparatus, where the attendant usually stands.

The shifting clutch member 11 is provided with a pair of collars 14, 14 between 25 which is arranged a cam 15 at the end of the rock shaft 2. This cam is so shaped and disposed that when the shaft has been turned to adjust the chute F to discharging position, the cam comes into engagement 30 with one of the collars 14 and moves the shifting clutch member into its intermediate position, thus stopping the chute-operating apparatus. When the shaft 2 is turned in the opposite direction to tilt the 35 chute inward and has been turned sufficiently far to bring the chute to its extreme position of inclination in this direction, the cam engages with the other collar and operates to disengage the clutch members and 40 bring the parts to rest. The driving mechanism described is thus automatically stopped whenever the chute reaches its limit of adjustment, whichever way it be moved, and thus the attendant is relieved of the necessity of watching the discharge end of the 45 apparatus after having once started the movement of the discharge chute.

I prefer to provide the toe or active end of the cam 15 with a roller 16 for the purpose of reducing friction.

The form of apparatus which I have illustrated in Figs. 4 and 5 differs from that shown in Figs. 1, 2 and 3 in that the shaft upon which the bevel pinions 8 8' are supported is vertically disposed instead of being horizontal. Such shaft is designated 6' and carries at its lower end a bevel wheel 17 that is driven by bevel pinion 18 upon the countershaft E. The other parts of the apparatus shown in Figs. 4 and 5 are so similar to the corresponding parts illustrated in Figs. 1, 2 and 3, and already described, that a further description of them seems to be unnecessary.

What I claim is:—

1. The combination with a receptacle and a tilttable chute therefor, of a rock-shaft connected with the chute for operating it, power-driven mechanism connected with the said shaft for oscillating it, including a manually operated clutch adapted to occupy a neutral position disconnecting the power mechanism from the oscillating shaft, but when shifted, in one way or the other, enabling the power to drive the shaft positively in either direction, and means connected directly with the rock-shaft for operating the clutch to move it to neutral position whereby the shaft is disconnected from the power mechanism when the chute arrives at its limit of inclination in either direction.

2. The combination with receptacle and a tilttable discharge chute therefor, of a rock shaft connected with the chute for tilting it, a gear wheel carried by the shaft, loosely mounted gear pinions engaging with the said gear wheel, a power-driven shaft, clutch mechanism under the control of an attendant for connecting one or the other of the said gear pinions with the power-driven shaft, and adapted to occupy a neutral position whereby the power shaft is disconnected from both the said gear pinions, and means carried by the rock shaft that operates the chute for shifting the clutch mechanism into its neutral position whenever the chute is inclined to the desired degree in either direction.

3. The combination with receptacle and a discharge chute therefor, of a rock shaft connected with the chute for tilting it, a bevel wheel upon the shaft, a horizontally mounted power-driven shaft, a pair of bevel pinions loosely mounted upon the power-driven shaft engaging with the bevel wheel at diametrically opposite points, a shifting clutch member splined to the power driven shaft arranged between the pinions and adapted to engage with either one or the other of them or to occupy a neutral position between them, shifting devices under the control of the attendant for operating the said clutch member, and a cam carried by the rock shaft that operates the chute for automatically disengaging the clutch member from the pinion with which it was engaged, and moving it into its neutral position, whenever the chute reaches the desired limit of adjustment.

4. The combination with a receptacle and a tilttable discharge chute therefor, of a rock-shaft connected with the chute for tilting it, power-driven means for positively driving the shaft, including a clutch arranged, accordingly as it is adjusted, to permit disengagement between the shaft and the source of power or connection therewith

so as to drive the shaft positively in either direction, eccentric, automatic, clutch-operating means supported directly by the said rock-shaft arranged to bring the clutch to neutral position disconnecting the rock-shaft from the source of power whenever the chute reaches the desired limit of movement in either direction, and manually con-

trolled devices for moving the clutch beyond the positions to which it is moved by the said automatic shifting means.
